GROUPING MECHANISM FOR VOTING-MACHINES.

No. 847,047.

Specification of Letters Patent.

Patented March 12, 1907.

Application filed December 26, 1906. Serial No. 349,651.

To all whom it may concern:

Be it known that we, WILLARD M. DELAVAN and ARTHUR B. CAMP, citizens of the United States, residing at Pittsfield, county 5 of Berkshire, State of Massachusetts, have invented a new and useful Grouping Mechanism for Voting-Machines, of which the following is a specification.

This invention relates to that portion of 10 the mechanism of a voting-machine that has to do with "group voting," so called. The term "group voting" is used as broadly descriptive of a style of voting which permits voters to vote for more than one candidate for 15 the same office—as, for example, in voting for a plurality of members of a board, commission, court, or a delegation of two or more members. Suppose, as an illustration, that a plurality of commissioners are to be elected 20 and that several parties have made nominations for that office.

The invention is shown as applied to a "vertical machine," so called, in which the names of party candidates are placed in vertical columns and the names of all candidates for the 25 same office are placed in horizontal lines, the name of each candidate being in its proper party-column; but the invention is of course equally applicable to a "horizontal machine," 30 so called, in which the names of party candidates are placed in horizontal lines and the names of candidates for the same office are placed in vertical columns. The machine is provided with horizontally-placed flexible 35 members corresponding with the horizontal lines of names of candidates, the act of voting being performed by movement of voting members, which when actuated produce a bend or slack in the corresponding flexible 40 member, each flexible member being tightened up, so as to have but one slack in it, thus making it normally impossible for a voter to vote for but one candidate for any office. In 45 the present instance we have shown the act of voting as performed by means of shafts which when oscillated cause corresponding locking-dogs to press upon the flexible members and make bends or slacks therein. We shall not describe the voting mechanism in 50 detail, however, for the reason that it forms no portion of the present invention.

The present invention consists in certain constructions and in certain parts, improve-

ments, and combinations to adapt a voting-machine for group voting which permit 55 groups of flexible members to be so connected up as to permit a number of votes corresponding with the number of flexible members in the group to be cast in accordance with the will of the voter, all in one line or in 60 different lines, as preferred, it being impossible, however, for the voter to cast but one vote for any candidate or more votes for the 65 office than there are flexible members in the group.

In the accompanying drawings, forming a part of this specification, in which reference characters are used to indicate the several parts, Figure 1 is an elevation of so much of the mechanism of a voting-machine as is necessary to illustrate the application of our invention thereto; Fig. 2, a section on the line 2 2 in Fig. 1 looking down, the flexible grouping member and flexible returning member being omitted; Fig. 3, a detail elevation, on a 75 larger scale, illustrating a form of the invention embodying an additional adjustment for the slides; Fig. 4, a plan view, on a still larger scale, of one of the slides in Fig. 3; Fig. 5, a detail elevation illustrating a form of the invention in which the flexible returning member is dispensed with and the slides are returned by other means, and Fig. 6 is a section on the line 6 6 in Fig. 5 looking down.

10 denotes the base of the machine; 11, the 80 top plate; 12, voting-member uprights or standards; 13, the grouping upright or standard; 14, the party-bars, which are provided with notches 15 and a rack 17; 16, voting members, and 19 party-levers, whose shafts 90 190 carry pinions 18, which engage the racks on the party-bars. The voting-member uprights are provided with lugs 21, by which the wedge-bars or resetting-slides 22 and the restrict-bars 23 are supported and on which 95 they slide longitudinally, and with vertical grooves 20, in which the party-bars slide. The voting members 16 comprise shafts 160, locking-lugs 161, and operating-levers 162. The party-lever shafts and voting-member shafts are journaled in front plate 24 and in the voting-member uprights. Lugs 21 on the lever-uprights serve the additional function of bracing and supporting the front plate, which is ordinarily secured thereto by 105 means of screws. (Not shown in the draw-

ings.) The front plate is in practice provided with ways (not shown) which receive ballot-strips in the usual manner. The restricting-bars 23 are secured, by means of screws 26, to 5 a vertical tie-bar 25, and wedge-bars or resetting-slides 22 are rigidly secured to a vertical tie-bar 27, reciprocatory motion being imparted to the wedge-bars or resetting-slides and to the restricting-bars through the 10 corresponding tie-bars by means not shown in the drawings.

28 denotes flexible members, in the present instance metallic strips, which lie under the locking-lugs of the voting members and are 15 bent or flexed thereby in the operation of voting, as clearly shown in the drawings. The right end of each flexible member is secured to some fixed part of the machine. (Not shown in the drawings.) The left end 20 of each flexible member is connected, as at 30, to a turnbuckle 32, which provides a means for adjusting the length of the flexible members in assembling the machine and also for tightening them should they become 25 stretched in use. The left end of the turnbuckle is rigidly secured to or formed integral with a slide 33. On opposite sides of the slides are flanged rollers 35 and 350, mounted to rotate on transverse pins 34, which pass 30 through the slides. In practice the ends of the pins are headed to retain the rollers in place. The grouping-upright, which as a 35 whole we have indicated by 12, comprises a back plate 36, a front plate 37, an end strip 38, and cross-pieces 39 at the right. The front and back plates are secured to the end strip and cross-pieces by means of screws or in any suitable manner. The front plate and back plate are provided with grooves 29, 40 lying intermediate the cross-pieces, in which flanged rollers 35 and 350 on the slides travel freely.

31 denotes pins secured in the front and back plates, on which flanged rollers 45 and 45 46 are mounted to rotate. These rollers lie in grooves 29 and are separated and retained in operative position by enlargements 47 on pins 31.

44 denotes a flexible grouping member, in 50 the present instance a metallic strip, which passes through the slides and alternately about rollers 350 on the slides and rollers 45 on pins 31. One end of the flexible grouping member is secured to a stud 40 in the grouping-upright, and the other end is secured to a threaded rod 48, which passes through an eye 49, which is rigidly secured to the upper end of the grouping-upright. Nuts 50 and 51 on opposite sides of the eye provide a means for 55 adjusting rod 48 to regulate the length of the flexible grouping member in assembling and for locking the rod in place after adjustment.

42 denotes a flexible returning member, in 60 the present instance a metallic strip, one end of which is rigidly secured to a stud 43 in the

grouping-upright. This flexible returning member passes through the slides and alternately about rollers 35 on the slides and rollers 46 on pins 31, then over flanged rollers 52 and 53, and is provided at its free end with a 70 weight 54 and a suitable shock-absorbing device, in the present instance a dash-pot comprising a tube 55, provided with openings 56 to permit escape of air, so that the weight will drop without shock and will return the 75 slides to their normal position after group voting.

In normal or regular voting the grouping flexible member is locked upon each pulley 45 by means of a friction-shoe 41, carried by 80 a screw 57, which passes through and engages end strip 38. These friction-shoes are held against rotation by means of pins 58, which pass into guide-holes in the shoes, each shoe being locked in position after adjustment by means of a lock-nut 59.

In setting up the machine the length of each flexible member is regulated to permit one slack therein and no more. This is effected by moving one voting member in each 90 line of voting members to the voting position and then taking up the extra slack in each flexible member by means of the turnbuckle. The length of the flexible grouping member is likewise regulated to permit one slack in 95 each line of grouping members and no more. This is effected by moving one voting member in each line of voting members to the voting position and then taking up the slack in the flexible grouping member by tightening 100 threaded rod 48 in eye 49 by means of nuts 50 and 51. This is a permanent adjustment and need not be changed unless to take up stretch in the flexible grouping member.

The operation is as follows: In Fig. 1 eight 105 lines of voting members are illustrated. The first line from the top is not grouped. The second, third, fourth, fifth, sixth, and seventh are grouped. In regular voting the slides 33 are all locked by locking flexible grouping 110 member 44, both sides of each slide. This is effected by moving friction-shoes 41 forward and clamping the flexible grouping member against rollers 45, which will be readily understood from Fig. 1 in connection with Fig. 2, in which a shoe is shown in the retracted position. When part of the lines of voting members are grouped and part not grouped, the rule for setting up the machine may be stated, as follows: The friction-shoes above 115 and below the slide belonging to each line of voting members not grouped are caused to clamp the flexible grouping member upon the corresponding rollers 45, and all friction-shoes between the upper and lower grouped 120 lines are moved out of engagement with the flexible grouping member, as clearly shown. It should be noted that the friction-shoe immediately above the first grouped line and the friction-shoe immediately below the last 125

grouped line must be in the clamping position, and, furthermore, that the friction-shoes on both sides of all lines not grouped must be in the clamping position.

5 It is of course well understood that voting machines are ordinarily provided with "entrance" and "exit" mechanism, so called, which are not illustrated, as they form no portion of the present invention. In the present 10 instance the operation of the entrance mechanism moves the wedge-bars or resetting slides from their normal or locking position toward the left to the position in which they are shown in Fig. 1, leaving the voting members unlocked and free to be operated, either 15 singly or by means of the party-levers. Operation of the voting members causes them to bend or flex the flexible members, which, as the right end of each flexible member is secured to a fixed part of the machine, (not shown,) draws the corresponding slides toward the right. When nothing but regular voting is to be provided for, all of the friction-shoes are moved forward and the flexible 20 grouping member is locked upon each roller 45, leaving the slides 33 all locked. In providing for group voting the friction-shoes between the first and last grouped lines are loosened, as already explained, this being all 25 that is required to set up lines of voting members for group voting—that is to say, it is simply necessary to release the grouping member its entire length between the first and last grouped lines, so that all the slides 30 between and including the first and last grouped lines are left free. Each time a voting member is operated the corresponding slide is moved toward the right the certain predetermined distance permitted by the 35 amount of slack in the flexible member. If a second voting member in the same line is operated, the corresponding slide is moved again the same distance toward the right, the required amount of slack being taken from 40 the slacks in the flexible members of the other grouped lines, the released flexible grouping member permitting the slides of the grouped lines to move freely. The same is 45 true if three or any other number of voting members in the same line are operated up to the entire number of grouped lines, it being understood, of course, that no more votes can be cast in any line than the entire number of grouped lines and that the votes may be 50 cast at will in the grouped lines, all in one grouped line, one in each grouped line, or any number in any grouped line up to the entire number of grouped lines. Each operation of a voting member after the first produces an 55 upward movement of the weight in tube 55 through the pull upon the flexible returning member made by movement of the slide toward the right. In practice the parts are so proportioned and adjusted and sufficient 60 friction is provided upon the voting mem-

bers to insure that while the voting members may be operated easily they will remain in the voting position when once placed there and the weight will remain in the raised position.

In Fig. 1 the first line from the top has not been grouped, and a vote has been cast in that line. The next seven lines have been grouped, one vote being cast in the second grouped line, one in the third, two in the 75 fourth, and three in the sixth grouped line, making seven votes cast in the group comprising the seven grouped lines.

After the completion of the voting operation the voter on leaving the machine operates exit mechanism, (not shown,) one of the functions of which is to move the wedge-bars or resetting slides from the position in Fig. 1 toward the right, whereby the locking-lugs of the voting members are engaged and the 80 voting members are returned to their normal or non-voting position—that is, to the position in which all the voting members appear in the first, fifth, and seventh grouped lines and are locked there. The instant the voting members are returned to their normal or non-voting position the weight will drop in the tube, but without shock, and the flexible grouping member will return the slides to their normal position, leaving the flexible 85 members taut and ready for the next voting operation.

The form illustrated in Figs. 3 and 4 differs from the form just described in unimportant details of construction, and, furthermore, in that we have provided an additional adjustment of the slides to provide for a condition in which there is a group of candidates to be voted for; but some of the parties for which the machine is to be set up, while they 100 have made nominations of candidates for offices to be voted for regularly, have made no nominations of candidates to be voted for in a group or have indorsed the nominations of some other party for the offices to be voted 105 for in a group. In this form the slides, which are indicated as a whole by 33, as before, consist of plates 60, secured together by cross-pins 61, with blocks 62 interposed between the plates, the pins passing through 110 the blocks. The rollers are mounted between the plates of the slides, and the slides themselves instead of the rollers engage and travel in slots 29 in the grouping-upright. The flexible members 28 are secured to the 115 blocks in each slide toward the front of the machine by being passed around it and then riveted, as at 63. In this form the slides carry rollers 35 and 350, as before, and rollers 120 45 and 46 are carried by pins 31, secured in the front and back plates of the grouping-upright. The flexible grouping member 44 passes alternately about rollers 350 and 45, (the latter not shown in this form,) as before, 125 and the flexible returning member 42 (not 130

shown in this form) passes alternately about rollers 35 and 46, as before. The friction-shoes 41 also operate in this form precisely as in the other form. The important feature of difference in this form is that each slide 33 has rigidly secured thereto a threaded rod 64, which passes loosely through end strip 38 of the grouping-upright. Each threaded rod is provided between the end of the slide and end strip 38 with a nut and set-nut (indicated together by 65) and on the opposite or outer side of strip 38 with a nut and set-nut, (indicated together by 66.) The turn-buckles are dispensed with in this form, and the adjustment of the length of the flexible members to permit the operation of a single voting member in each line and to take up the stretch of use is effected by means of nuts 65. When it is not desired to use nuts 66, as in regular voting or in ordinary group voting, said nuts may be removed from the rod or turned out far enough toward the outer ends thereof to be inoperative and left there. In case, however, that all of the parties in the field have not made nominations for the offices to be voted for in a group then nuts 66 are brought into use. It should be understood that when nuts 66 are not used the operation is precisely the same as has been described in connection with Fig. 1. There is no objection, however, to using nuts 66 for regular voting. For regular voting said nuts 66 are so adjusted on rods 64 as to permit one slack in the flexible member and no more—as, for example, in the upper line in Fig. 3—which, it will be noted, is set for regular voting by the engagement of friction-shoes 41 with the flexible grouping member on the corresponding rollers 45 above and below this line. The second, third, fourth, fifth, and sixth lines are shown as set for group-voting, and nuts 66 must be so adjusted on rods 64 as to permit as many slacks in each flexible member as there are nominations in that line. For example, if there are three nominations in a line the nuts 66 on the rod 64 corresponding to that line are turned outward on the rod just far enough to permit three slacks to be placed in the flexible member corresponding to that line and no more, so that when three slacks have been placed in that flexible member the nuts 66 will be drawn into engagement with the outer face of end strip 38 and will render it impossible to place any more slacks in that flexible member.

In Fig. 3 the nuts 66 on the grouped lines—that is, the second, third, fourth, fifth, and sixth lines—are set to permit three slacks in the flexible member corresponding with each grouped line, as in a condition where five offices are to be voted for in a group but three parties only have placed candidates in nomination for these offices. As indicated, one vote has been cast in the first grouped

line, two in the third, and two in the fourth and none in either the second or fifth grouped lines. The use of rods 64 and nuts 66 in addition to rendering it impossible for a voter to vote for more candidates in a line than there are nominations in that line renders it impossible for a voter to deprive himself of his rightful vote by manipulating voting members in party-columns in which no nominations have been made for the offices to be voted for in a group.

The form illustrated in Figs. 5 and 6 differs from the forms illustrated in Figs. 1 and 2 and Figs. 3 and 4 in that a chain is substituted for a metallic strip as a flexible grouping member and the flexible returning member and with it rollers 35 and 46 are dispensed with. The slides consist of plates secured together by rivets or otherwise and are returned to their normal position after a voting operation by different means, and a variant form of connection to the slides is provided for the flexible members. The rollers are mounted between the plates of the slides, and the slides themselves engage the grooves 29 in the grouping-upright, as in Figs. 3 and 4. The links of the chain employed as a flexible grouping member are shown as provided with concave sides and the pitch is such as to place the mid-length of a link in position to be engaged by the end of each screw 57, thus doing away with the friction-shoes used in the other forms; otherwise the operation of screws 57 to lock the flexible grouping member to rollers 45 is the same as in the other forms, the difference being that the ends of the screws engage the flexible grouping member instead of friction-shoes. The flexible members (not shown in this form) are connected to the slides by means of threaded rods 67, which pass through the ends of the slides and are adjusted to give the required length to the flexible members by means of nuts 68, which engage the rods and bear against the end walls of openings 69 in the slides. The operation of setting up the machine for either regular or group voting is the same as that illustrated in Figs. 1 and 2. In this form the machine is shown as set up for regular voting. To set up for group voting, it is simply necessary to loosen all screws 57 between the first and last lines to be grouped as before. After a voting operation the slides are returned to their normal position by means of a vertical returning bar or bars 70. These bars are moved laterally toward the right by the entrance mechanism and connections (not shown) to release the slides and are moved laterally toward the left by the exit mechanism and connections (not shown) to return the slides to their normal position.

Having thus described our invention, we claim—

1. In a voting-machine the combination of

- flexible members, slides to which they are connected, a flexible grouping member passing through the slides, means for locking the flexible grouping member both sides of each slide and means for returning the slides to their normal position after a voting operation.
2. In a voting-machine the combination of flexible members, slides to which they are connected, means for adjusting the length of the flexible members, means for locking the flexible grouping member both sides of each slide and means for returning the slides to their normal position after a voting operation.
3. In a voting-machine the combination of flexible members, slides to which they are connected, turnbuckles intermediate the flexible members and the slides, a flexible grouping member passing through the slides, means for locking the flexible grouping member both sides of each slide and means for returning the slides to their normal position after a voting operation.
4. In a voting-machine the combination of flexible members, slides to which they are connected, a grouping-upright in which the slides reciprocate, a flexible grouping member passing through the slides each end being connected to the upright, means for locking the flexible grouping member both sides of each slide and means for returning the slides to their normal position after a voting operation.
5. In a voting-machine the combination of flexible members, slides to which they are connected, rollers 350 on the slides, a grouping-upright in which the slides reciprocate and which is provided with rollers 45, a flexible grouping member connected to the upright above and below the slides and passing alternately about the rollers on the slides and the upright, means for locking the flexible grouping member to rollers 45 and means for returning the slides to their normal position after a voting operation.
6. In a voting-machine the combination of flexible members, slides to which they are connected, rollers 350 on the slides, a grouping-upright having grooves in which said rollers travel and which is provided with rollers 45, a flexible grouping member connected to the upright above and below the slides and passing alternately about the rollers on the slides and the upright, means for locking the flexible grouping member to rollers 45 and means for returning the slides to their normal position after a voting operation.
7. In a voting-machine the combination of flexible members, slides to which they are connected, a grouping-upright in which the slides reciprocate, a flexible grouping member passing through the slides and connected to the upright at each end, one of said connections being adjustable, means for locking the flexible grouping member both sides of each slide and means for returning the slides to their normal position after a voting operation.
8. In a voting-machine the combination of flexible members, slides to which they are connected, a grouping-upright in which the slides reciprocate, a flexible grouping member passing through the slides and connected to the upright below the slides, an eye on the upright above the slides, a threaded rod passing loosely through the eye to which the upper end of the flexible grouping member is connected, and nuts engaging said rod and the opposite sides of the eye by which the flexible grouping member is adjusted.
9. In a voting-machine the combination of flexible members, slides to which they are connected, a grouping-upright in which the slides reciprocate, a flexible grouping member passing through the slides, means for adjusting the length of the flexible members and the flexible grouping member, and means for locking the flexible grouping member above and below each slide.
10. In a voting-machine the combination of flexible members, slides to which they are connected, rollers 350 on the slides, a grouping-upright in which the slides reciprocate and which is provided with rollers 45, a flexible grouping member connected to the upright and passing alternately about the rollers on the slides and the upright, friction-shoes for clamping the flexible grouping member to rollers 45, and screws engaging the upright by which the friction-shoes are carried.
11. In a voting-machine the combination of flexible members, slides to which they are connected, rollers 350 on the slides, a grouping-upright in which the slides reciprocate and which is provided with rollers 45, a flexible grouping member connected to the upright and passing alternately about the rollers on the slides and the upright, friction-shoes for clamping the flexible grouping member to rollers 45, screws passing through the upright, by which the friction-shoes are carried, pins extending from the upright and engaging the shoes, and set-nuts for locking the shoes after adjustment.
12. In a voting-machine the combination of flexible members, slides to which they are connected, rollers 35 and 350 on the slides, a grouping-upright in which the slides reciprocate and which is provided with rollers 45 and 46, a flexible grouping member connected to the upright and passing alternately about rollers 45 and 350, a flexible returning member connected to the upright below the slides and passing alternately about rollers 35 and 46, and a weight connected to the flexible returning member.
13. In a voting-machine the combination of flexible members, slides to which they are connected, rollers 35 and 350 on the slides, a

- grouping-upright in which the slides reciprocate and which is provided with rollers 45 and 46, a flexible grouping member connected to the upright above and below the slides, and passing alternately about rollers 45 and 350, a flexible returning member connected to the upright below the slides and passing alternately about rollers 35 and 46, rollers above the slides over which the flexible returning member passes, a weight on said member and a dash-pot in which the weight slides.
14. In a voting-machine the combination of flexible members, slides to which they are connected, a flexible grouping member passing through the slides and means for locking the flexible grouping member both sides of each slide.
15. In a voting-machine the combination of voting members, flexible members engaged thereby in the operation of voting, slides to which the flexible members are connected, a flexible grouping member passing through the slides, means for locking the flexible grouping member both sides of each slide, means for returning the voting members and means for returning the slides after a voting operation.
16. In a voting-machine the combination of voting members provided with locking-lugs, flexible members engaged thereby in the operation of voting, slides to which the flexible members are connected, a flexible grouping member passing through the slides, means for locking the flexible grouping member above and below each slide, means for returning the slides after a voting operation and reciprocating wedge-bars which engage the locking-lugs to reset the voting members after a voting operation.
17. In a voting-machine the combination of flexible members, slides to which they are connected, a grouping-upright in which the slides reciprocate, threaded rods extending from the slides and passing through the upright, nuts on said rods for determining the number of slacks given to the flexible members, for the purpose set forth, a flexible grouping member passing through the slides to which they are connected, a grouping-upright in which the slides reciprocate and which is provided with an end strip 38, threaded rods extending from the slides and passing through said end strip, a nut 65 on said rod between the slides and the end strip, a nut 66 on said rod outside the end strip, for the purpose set forth, a flexible grouping member passing through the slides and connected to the upright and means for locking the flexible grouping member both sides of each slide.
18. In a voting-machine the combination of flexible members, slides to which they are connected, a grouping-upright in which the slides reciprocate and which is provided with an end strip 38, threaded rods extending from the slides and passing through said end strip, a nut 65 on said rod between the slides and the end strip, a nut 66 on said rod outside the end strip, for the purpose set forth, a flexible grouping member passing through the slides and connected to the upright and means for locking the flexible grouping member both sides of each slide.
19. In a voting-machine the combination of voting members provided with locking-lugs, flexible members engaged thereby in the operation of voting, voting-member uprights provided with lugs 21, slides to which the flexible members are connected, a flexible grouping member passing through the slides, means for locking the flexible grouping member above and below each slide, means for returning the slides after a voting operation and reciprocating wedge-bars supported by lugs 21 which engage the locking-lugs to reset the voting members.
20. In a voting-machine the combination of slides, a flexible grouping member passing through said slides and means for locking the flexible grouping member both sides of each slide.
21. In a voting-machine the combination of slides, a grouping-upright in which they reciprocate, a flexible grouping member passing through the slides and connected to the upright and means for locking the flexible member both sides of each slide.
